SCREENING APPARATUS AND THE LIKE

Walter Joseph Parks, Cleveland, Ohio

Application July 22, 1936, Serial No. 91,979

10 Claims. (Cl. 209—326)

This invention relates generally to certain new and useful improvements in screen machines or apparatus for use in connection with the screening of materials and like operations but more particularly to the gyratory type of screen machine wherein the gyrating screen body is mounted on or stabilized by resilient means.

One of the objects of the invention is to provide a resilient supporting means for the gyrating bodies of machines of this character which is so designed and constructed as to be economical and efficient and structurally sound and durable.

Another object is the provision of a screening machine having a plurality of gyratory screen bodies operatively connected with a unitary actuating mechanism for positively gyrating such bodies and wherein resilient means are provided for supporting the screen bodies and actuating mechanism in such a manner as to provide proper constraint and stability for such parts.

Other features of the invention reside in the construction and arrangement of parts herein-after described and particularly pointed out in the appended claims.

23 In the accompanying drawings:

Fig. 1 is a side elevation of the screening apparatus embodying my invention. Fig. 2 is a top plan view of the same. Fig. 3 is an enlarged fragmentary cross section taken in the plane of line 3—3, Fig. 2. Fig. 4 is an enlarged transverse section taken on line 4—4, Fig. 1, showing one of the resilient supports or mountings of the screen body. Fig. 5 is an enlarged cross section taken on line 5—5, Fig. 3. Fig. 6 is a sectional elevation of a modified form of resilient mounting. Fig. 7 is a side elevation of a modified form of screening apparatus embodying a plurality of gyratory screen bodies. Fig. 8 is a top plan view thereof. Fig. 9 is an enlarged fragmentary cross section taken on line 9—9, Fig. 8. Fig. 10 is an enlarged transverse section taken on line 10—10, Fig. 8. Fig. 11 is a cross section taken on line 11—11, Fig. 10. Fig. 12 is a detached diagrammatic side elevation of the drive or crank shaft 45 of the screen shown in Fig. 9. Fig. 13 is a diagrammatic perspective view thereof. Fig. 14 is a diagrammatic view showing the disposition of the eccentric centers of such crank shaft. Fig. 15 is a transverse section of a modified form of the 50 mounting shown in Fig. 10. Fig. 16 is a cross section thereof taken on line 16—16, Fig. 15.

Similar characters of reference indicate corresponding parts throughout the several views.

By way of example, my invention has been 55 shown in connection with an apparatus for

screening materials, and in the embodiment thereof shown in Figures 1—5, inclusive, 15 indicates the stationary base or supporting frame which may consist of channel rails mounted on appropriate supports, and 16 the screen body or live frame which is freely or resiliently suspended from the base and to which a gyratory motion is imparted for effectually screening the materials delivered thereto.

Adjacent its ends and at opposite sides thereof, 10 the screen body 16 is supported from the base rails 15 on resilient mountings which serve to provide constraint for the screen body in all directions as well as to provide for its proper stability during screening operations. By preference, these mountings consist of rubber members or blocks 17 which may be round in cross section and which are so disposed and mounted that the load is carried in shear by these rubber members and the displacement caused by the gyrating motion of the screen body is also accompanied by a shear displacement in the rubber member. Each of these rubber members is provided on its opposite faces with parallel attaching plates 18, the rubber member being cured thereto to form a 25 substantially unitary structure. Each of these rubber units or assemblies is secured at one side to a bracket 19 attached to the supporting frame 15 and at its opposite side to a bracket 20 secured to the adjoining side wall of the gyratory screen frame 16. In the preferred form of each rubber mounting, as clearly shown in Fig. 4 two rubber units are employed, these units being disposed laterally of the machine in aligned or end to end relation and with their axes inclined in opposite 30 directions and disposed obliquely to the horizontal. By the inclined disposition of the rubber members 17, when a load is placed on the screen body 16, the displacement results in a compression force acting on the rubber and squeezing it 35 between the attaching plates 18. The greater the load, the more the displacement and the greater the compression force within the safe load of the mounting. This compression force acting between the rubber and its attached plates increases 40 the allowable unit shear stress at this point and increases the safety of the unit.

45 This angular mounting is particularly desirable from a safety standpoint inasmuch as the bond between the rubber and steel is weakened in tension, strongest in compression and intermediate in shear strength. By the mounting shown and described, the compression force introduced prevents a tension stress in the bond within any deflection encountered in the use of the machine, 50 55

because any downward displacement of the outer housing results in a compression of the rubber between the steel plates, thereby increasing its load-carrying ability. In addition, this compression stress is small for the amplitude of gyration of the machine and so does not affect its smooth operation in machines where such smoothness depends on equal and opposite reactions being developed in these resilient units, such for example as the machine shown in Fig. 1. With the shear rubber mountings the least change of volumes in the rubbers will take place for a given displacement of the load, and there is provided a flexible mounting which is efficient and economical. Furthermore by the dual mounting shown, the compression component of the force exerted by the rubbers as they are deflected balance each other and thereby reduces the necessity of heavy bracing for the supporting frame.

If desired, and as shown in Figs. 4 and 5, the brackets 20 may be shaped to form housings or casings for the rubber mountings 17, 18.

In the screening apparatus to which I have applied my improved shear mountings, the screen body 16 is supported for gyratory movement on a transverse driving shaft 21 which passes through the side walls of said body and which is supported at its ends in free-floating fashion in companion, resilient gyratory supporting bodies 22. This drive shaft is provided adjacent its opposite ends with offset crank portions or eccentrics 23, 24 which are preferably of equal magnitude and 180 degrees apart. As shown in Fig. 3, the inner crank portion 23 engages a corresponding roller or like bearing 25 fitted in the adjoining side wall of the screen body while the outer crank portion 24 engages a like bearing 26 fitted in the companion supporting body 22. At one end the shaft 21 is provided with a pulley 27 for driving connection to a source of power. Also mounted on this shaft are counterweighted fly wheels 28.

The gyratory supporting bodies 22 for the drive shaft 21 are resiliently supported on the stationary base in the same manner as the screen body 16, that is, by rubber mountings 17^a disposed in shear and attached to brackets 19^a secured to the base 15 and to brackets 20^a secured to or constituting a part of the ends of the gyratory bodies 22.

In the modified form of resilient mounting shown in Fig. 6, the shear rubbers consist of annular members or rings 29 cured to like-shaped fittings or attaching rings 30, 31, the fitting 30 being secured to a bracket 32 attached to the supporting base 15^a of the machine and the fitting 31 being applied to the ends of a spacing bar or rod 33 extending transversely thru the screen-body 16^a. It will be noted that the annular rubber rings 29 are disposed in pairs with one at each side of the bracket 32 and that the screen body is carried by these rubbers in shear.

In Figs. 7-14 inclusive, I have shown a screening machine embodying a plurality of gyratory screen bodies, 34, 35 actuated by a common drive shaft 36 extending transversely through such bodies and supported at its opposite ends in free-floating fashion in companion, resilient supporting bodies 37, similar to those indicated at 22 in the first-described machine. In this case, however, the drive shaft is provided adjacent its ends with three offset crank portions or eccentrics 38, 39 and 40 which are of equal magnitude and 120 degrees apart, with the masses of the gyratory bodies and counterweighted balance wheels, as 75 and when necessary, so proportioned that the

self-determined axis of revolution is equidistant from the center of each crank or eccentric. As shown in Fig. 9, the crank portion 38 engages a corresponding roller or like bearing 41 fitted in a bearing housing 42 applied to the adjoining side wall of the lower screen body 35 which is disposed below the drive shaft 36; the crank portion 39 engages a similar bearing 43 fitted in a bearing housing 44 applied to the adjoining side wall of the upper screen body 34 which is disposed over the drive shaft; and the crank portion 40 engages a like bearing 45 fitted in the companion supporting body 37. At one end the shaft is provided with a drive pulley 46 and adjacent each end with counterweighted fly wheels 47. It will be further noted from Fig. 9 that the side walls of the respective screen bodies are in vertical alignment or in a common plane and sufficient space is provided between the opposing edges of these side walls, as seen in Fig. 7, to allow for the gyrating movements of these screen bodies.

The screen bodies 34, 35 and the gyratory supporting bodies 37 are resiliently supported by rubber in shear in the same manner as described in the previous construction, suffice it to say that, as shown in Fig. 11, the rubber mountings have their rubber members 48 disposed horizontally and attached to brackets 49 and 50 secured to the supporting frame 51 and screen bodies, respectively. Likewise, the supporting bodies 37 are carried by rubbers in shear and are indicated generally by the numerals 52, being identical in construction to those of the supporting bodies 22. This arrangement of parts reduces the loads on the screen bearings over those the eccentric bearings would have to bear if both screen bodies were a unit and carried by one pair of bearings.

From the foregoing screen arrangement, it is to be understood that any other combination of eccentrics could be used at other regular angular displacements to actuate any given number of bodies, the center of rotation being determined as before between the various eccentric centers as determined by the relative masses and eccentricities desired.

In the embodiment of the resilient mounting depicted in Figs. 15 and 16, it is substantially the same as that shown in Figs. 10 and 11, with the exception that the rubber member 53 is molded so that the attaching plates 54 and 55 are diametrically displaced rather than in alignment. When this mounting is placed in the machine, the attaching plates are vertical and the rubber member extends obliquely from one plate to the other. In other words, assume plate 54 being attached to the fixed bracket 56 with its face vertical and the companion plate 55 attached to the gyratory housing 57 with its face vertical and parallel to that of 54. Then the oblique molding or disposition of the rubber, with its central axis at an oblique angle to the faces of the plates, will elevate plate 55 above plate 54, as shown. If a load be imposed on the mounting through the housing-bracket 57, then the unit will deflect. This deflection will shorten the length of the rubber member on a line parallel to its central axis and thus introduce a compression force similar to that of the angular mountings of Fig. 4. This compression will increase until the axis of the rubber itself is substantially horizontal and will then decrease as the angle increases downwardly. The deflection can be so controlled, however, by proper and safe loading, that the compression never changes to a tension stress at the bond be- 75

tween the rubber and the steel. This mounting has the advantage that during gyration of the parts, the attaching plates 54, 55 move parallel to each other with all points of their faces in a vertical plane parallel to the movement of the machine, and thus no unbalanced compression forces exist when used on a machine of the type shown in Fig. 1, where the smoothness of operation is, to a considerable extent, determined by 10 the equal and oppositely directed reactions in the resilient units.

I claim as my invention:

1. In a machine of the character described, a vibratory body, a supporting frame, a drive shaft for said body extending transversely thereof between the ends thereof, connections between said shaft and said body for vibrating the latter in planes perpendicular to the shaft-axis, and rubber members disposed at opposite sides of the 20 shaft-axis, and mounted in shear laterally between said frame and said body for normally sustaining said body in load-carrying position, said rubber members having their periphery surfaces exposed and unrestrained and being displaceable in shear in planes at right angles to the shaft-axis.

2. In a machine of the character described, a vibratory body, a supporting frame, a drive shaft extending transversely of said body, connections 30 between said shaft and said body for vibrating the latter, in planes perpendicular to the shaft-axis, and means including rubber members interposed transversely between said supporting frame and said body with their end faces, opposing said frame and said body, disposed in planes at substantially right angles to said shaft to support the body in load-carrying position and adapted to be displaceable in shear in planes at right angles to the shaft-axis during vibratory 40 movements of said body.

3. In a machine of the character described, a vibratory body, a supporting frame, a drive shaft extending transversely of said body, connections between said shaft and said body for 45 gyrating the latter in planes perpendicular to the shaft-axis, and resilient means for supporting and stabilizing said body at opposite sides of said shaft consisting of rubbers mounted for displacement in shear in planes at right angles to the shaft-axis and interposed between said supporting frame and said body with their axes extending generally transversely of such parts, and attaching plates to which the opposite ends of 50 said rubbers are cured to form substantially unitary structures, the peripheral surfaces of said rubbers being exposed and unrestrained and said plates being arranged at substantially right angles to the shaft-axis and secured to the supporting frame and the vibratory body, respectively.

4. In a machine of the character described, a vibratory body, a supporting frame, a drive shaft for said body, connections between said shaft and said body for gyrating the latter, in planes 65 perpendicular to the shaft-axis, and resilient means for supporting and stabilizing said body at opposite sides of said shaft consisting of rubber units of substantially circular cross section mounted in shear and interposed laterally between said supporting frame and said body with their peripheral surfaces free and unrestricted and with the axes thereof disposed in planes substantially parallel to the shaft and obliquely to the horizontal, said rubbers being displaceable in 70 shear at right angles to the shaft-axis.

5. In a machine of the character described, a vibratory body, a supporting frame, a drive shaft for said body, connections between said shaft and said body for gyrating the latter in planes at right angles to the shaft-axis, and resilient means at opposite sides of the body for supporting and stabilizing it at opposite sides of said shaft consisting of rubber units mounted in shear and interposed laterally between said supporting frame and said body, each rubber unit consisting of oppositely-inclined rubber members disposed in substantially alining relation crosswise of the machine and each member being secured at one end to the supporting frame and at its other end to the vibratory body, said rubber members being displaceable in shear in planes at right angles to the shaft-axis.

6. In a screening machine, a vibratory screen body, a supporting frame, a drive shaft for said body, connections between said shaft and said body for gyrating the latter in planes perpendicular to the shaft-axis, and resilient means for supporting and stabilizing said body at opposite sides of said shaft consisting of brackets applied to said supporting frame and to said body, 20 respectively, in laterally spaced relation, and rubber members extending from opposite sides of said frame-brackets and disposed between and secured at their opposite ends to the companion brackets of the screen body, said rubber members 30 being so constructed and arranged as to be displaceable in shear in planes at right angles to the shaft-axis.

7. In a machine of the character described, a supporting frame, a plurality of resiliently-supported bodies, a drive shaft solely supported by said bodies, means for resiliently supporting said bodies and including rubber members mounted in shear and interposed laterally between said frame and said bodies and sustaining said bodies in load-carrying position while permitting gyration of the bodies in vertical planes, and connections between said shaft and said bodies for positively gyrating them in paths lying in planes at right angles to said shaft.

8. In a machine of the character described, a stationary base, a resiliently-supported gyratory body for treating materials, a drive shaft extending through said body, resiliently-supported gyratory bodies at opposite sides of the material-treating body and through which the drive shaft extends, said bodies constituting floating supports for said shaft, eccentric means on said shaft and engaging said bodies, respectively, for gyrating them, and means for resiliently supporting said bodies in load-carrying position and permitting their gyration in vertical planes, each of said resilient supporting means consisting of rubber members mounted in shear and interposed between said base and said companion body.

9. In a machine of the character described, a stationary base, gyratory bearing-bodies resiliently supported on said base, a pair of superposed screen bodies independently resiliently mounted on said base between said bearing-bodies, and a drive shaft journaled in said bearing-bodies and said screen bodies and extending between the latter, said shaft having eccentrics thereon angularly displaced at 120 degrees apart for gyrating said bearing-bodies and said screen 65 bodies about a self-determined axis lying between the axes of said eccentrics.

10. In a machine of the character described, a stationary base, a pair of superposed vibratory bodies for treating materials having alining 70

75

bearings, a drive shaft engaging said bearings, connections between said shaft and said body-bearings for gyrating the bodies, at planes at right angles to the shaft-axis, and resilient means for supporting and stabilizing said bodies at opposite sides of said shaft and consisting of rub-

ber members mounted in shear and laterally between said base and said bodies to be subjected to a universal shear displacement in planes at right angles to the shaft-axis during the gyroscopic movements of said bodies.

WALTER JOSEPH PARKS.
